SCREW HOLDING SCREW DRIVER

Roy H. Alexander, Guam, Guam

Application January 13, 1948, Serial No. 2,002

4 Claims. (Cl. 145—52)

1

This invention relates to screwdrivers and more particularly to a screwdriver adapted to grip a screw so that it may be started and to thereafter release the screw so that it may be driven in the normal manner.

A main object of the invention is to provide a novel and improved screwdriver of the screw-gripping type which is adapted to firmly grip the screw while it is being started, thereby eliminating the need for drilling a hole to receive the screw prior to driving it.

A further object of the invention is to provide an improved screwdriver of the screw-gripping type wherein the screw-gripping force is increased responsive to pressure applied to the screwdriver handle during the screw starting process, said screwdriver being relatively simple in construction, easy to manipulate and inexpensive to manufacture.

Further objects and advantages of the invention will become apparent from the following description and claims, and from the accompanying drawings, wherein:

Figure 1 is a longitudinal cross-sectional view taken through a screwdriver constructed in accordance with the present invention, the screw-gripping means thereof being shown in spread position immediately prior to engagement with a screw.

Figure 2 is a longitudinal cross-sectional view similar to Figure 1 but showing the screwdriver in screw-gripping position.

Figure 3 is a fragmentary cross-sectional detail view of the forward portion of the screwdriver of Figure 1, showing the screw-gripping means retracted to inoperative position whereby the screw driver may be employed in the normal manner to complete the driving of the screw.

Figure 4 is a transverse cross-sectional detail view taken on line 4—4 of Figure 1.

Figure 5 is a fragmentary elevational view of the forward portion of the screwdriver of Figure 1, with the screw-gripping means shown in normal position prior to being placed in the spread position of Figure 1.

Referring to the drawings, 11 designates the shank of the screwdriver, said shank being formed at its forward end with a reduced bit 12 having a blade portion 13 adapted to interlock with the driving groove of a conventional screw, such as shown at 14. Secured transversely in bit 12 is a bolt member 15 formed with laterally projecting headed ends 16, 16. Surrounding the intermediate portion of shank 11 and longitudinally slidably thereon is a sleeve member 17. 55

2

Pivottally connected to the forward end portion of sleeve member 17 on a common transverse axis are channel-shaped jaw members 18, 18 embracing the forward end of shank 11 and formed with forwardly flaring cam surfaces 19, 19 at their forward end portions and with inwardly tapering concave gripping seat elements 20, 20 at their forward ends. The cam elements 19, 19 are longitudinally slotted at 21, 21 to receive the transverse bolt member 15, the heads 16, 16 of said bolt member bearing externally on said cam elements.

Rigidly secured to the rear portion of the sleeve member 17 is an annular flange 22. Designated at 23, is a hollow handle member housing the rear end portions of shank 11 and sleeve member 17 and formed with a forward sleeve portion 24 provided with an inturned annular end flange 25 slidable on sleeve member 17. Encircling the sleeve member 17 and bearing between flange 25 and flange 22 is a coiled spring 26 which biases the sleeve member 17 rearwardly with respect to handle flange 25.

The rear end portion of shank 11 is formed with a slot 27 and rotatably secured to the shank in said slot is a gear 28, the hollow handle member 23 being formed with upper and lower keyways 29, 29' in the same longitudinal plane in which said gear is located. Secured rigidly in the keyway 29 at one side of the shank 11 is a first rack bar 30 meshing with gear 28. Longitudinally slidable in the keyway 29' at the other side of shank 11 is a second rack bar 31, also meshing with gear 28. The edge of rack bar 31 is notched at 32. Pivottally secured in a recess 33 formed in the wall of the handle member 23 adjacent rack bar 31 is a detent lever 34 biased clockwise, as viewed in Figure 1, by a spring 35 bearing between the detent lever and the recess wall. One end of detent lever 34 is adapted at times to interlock with the notch 32 in rack bar 31 by the biasing action of spring 35. The other end of said lever carries a release button 36 which projects externally of the handle member 23 for rotating said lever manually to disengage it from the notch 32.

In the normal position of the screwdriver, spring 26 acts to maintain flange 22 in abutment with the forward end of rack bar 31. The rack bar 31 is so dimensioned that under these conditions the bolt member 15 is about midway in the cam slots 21, 21 and the heads 16, 16 of said bolt member engage the intermediate portions of the cam elements 19, 19 and thereby hold the jaw elements 18, 18 in their partly

closed positions, shown in Figure 5. To engage the head of a screw, the sleeve member 17 is held and the handle member 23 is pulled rearwardly. Force is thereby transmitted to shank 11 to retract shank with respect to sleeve member 17 to the position shown in Figure 1, whereby the heads 16, 16 of bolt member 15 travel to the rear ends of the slots 21, 21. In this position lever 34 is engaged in notch 32. This allows the jaw members 18, 18 to be separated sufficiently to receive the head of a screw 14 within the concave seat elements 20, 20 with the blade tip 13 engaged in the kerf of the screw. Lever 34 is then released by pushing button 36 and handle 23 is then moved forwardly with respect to sleeve member 17, causing shank 11 to be moved forwardly and moving the bolt heads 16, 16 forwardly on the flaring cam surfaces 19, 19 to return the jaw members 18, 18 to positions such as shown in Figure 2, wherein the head of screw 14 is clamped by the concave seat elements 20, 20. The screw may then be started and driven into its intended location.

As forward pressure is applied to handle 23 during the screw starting process, gear 28 is rotated counter-clockwise, as viewed in Figure 2, by the forward movement of rack bar 30. This causes rack bar 31 to be moved rearwardly. As rack bar 31 moves rearwardly out of abutment with flange 22, the expansive force of spring 26 is applied entirely to said flange and acts on sleeve member 17 to urge said sleeve member rearwardly with respect to shank 11. This wedges bolt heads 16, 16 more firmly against the forwardly flaring cam surfaces 19, 19 and tightens the grip of the jaw members 18, 18 on the screw head.

After the screw has been started and it is no longer necessary to clamp it to the screwdriver bit, the screw may be released by holding the sleeve member 17 and pulling rearwardly on the handle member 23. This rotates gear 28 clockwise, as viewed in Figure 2, and moves rack bar 31 forwardly into abutment with flange 22, thereby exerting a rearward pull on shank 11 with respect to the sleeve member 17. When shank 11 moves rearwardly with respect to said sleeve member, the bolt heads 16, 16 travel rearwardly on the cam surfaces 19, 19 and release the jaws 18, 18 allowing the screw head to be disengaged from between the concave gripping elements 20, 20. After the screw head has been thus disengaged, handle member 23 is pushed forwardly with respect to sleeve member 17, causing the rack bar 31 to be retracted until the detent lever 34 enters the notch 32 in said rack bar. This operation also causes the spring 26, acting through flange 25, handle 23, rack bar 30, and gear 28 to move the shank 11 forwardly with respect to sleeve member 17 until the gripping elements 20, 20 are in the inoperative positions thereof, shown in Figure 3, engaging the opposite surfaces of the blade 13 of the screwdriver bit. Since the detent lever 34 when seated in notch 32, opposes any further forward movement of handle member 23 with respect to rack bar 31, forward pressure on the handle member will be transmitted directly to shank 11 through the rack bars 30 and 31 and gear 28, whereby the screwdriver may be employed in the driving of the screw. After the operation is completed, the push button 36 is pressed inwardly, releasing the rack bar 31 and allowing the parts to be returned to their normal positions illustrated in Figure 5.

While a specific embodiment of a screwdriver of the screw-gripping type has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

10. In a screwdriver, a shank member having a bit portion adapted to engage the kerf of a screw, a sleeve member slidable on said shank member, a plurality of jaw elements secured to said sleeve member, inter-engaging means on said shank member and jaw elements formed and arranged to contract said jaw elements responsive to rearward axial movement of said sleeve member with respect to said shank member, a handle member slidable on said sleeve member, inter-engaging means carried by said handle member and shank member, a portion of said latter inter-engaging means being longitudinally movable with respect to said handle member responsive to sliding movement of the handle member on said sleeve member and being formed and arranged to act between the sleeve member and the shank member to produce relative axial movement of the shank member with respect to the sleeve member in one direction, and spring means biasing the sleeve member for movement relative to the shank member in the opposite direction.
20. In a screwdriver, a shank member having a bit portion adapted to engage the kerf of a screw, a sleeve member slidable on said shank member, a plurality of jaw elements pivotally secured to said sleeve member, inter-engaging cam means on said shank member and jaw elements formed and arranged to contract said jaw elements responsive to rearward axial movement of said sleeve member with respect to said shank member, a handle member slidable on said sleeve member, a bar element slidably carried in said handle member and bearing on said sleeve member to oppose rearward movement thereof, respective spaced abutment elements on said handle member and sleeve member located forwardly of said bar element, a spring disposed between said abutment elements and being formed and arranged to bias the sleeve member rearwardly in opposition to said bar element, and inter-engaging means carried by said shank member and handle member and being formed and arranged to move said bar member out of engagement with said sleeve member responsive to forward movement of the handle member on said sleeve member.
30. In a screwdriver, a shank member having a bit portion adapted to engage the kerf of a screw, a sleeve member slidable on said shank member, a plurality of jaw elements pivotally secured to said sleeve member, inter-engaging cam means on said shank member and jaw elements formed and arranged to contract said jaw elements around the kerf-engaging portion of the shank member responsive to rearward axial movement of said sleeve member with respect to said shank member, a handle member slidable on said sleeve member, a gear carried by said shank member, a first rack bar rigidly carried by said handle member and meshing with said gear, a second rack bar slidably in said handle member and also meshing with said gear, said rack bars meshing with the gear at diametrically opposite points on the gear, said second bar

normally bearing on said sleeve member to oppose rearward movement thereof with respect to said shank member, and a spring bearing between the handle member and sleeve member in opposition to said second rack bar, said spring being formed and arranged with respect to the handle member and sleeve member to move the sleeve member rearwardly with respect to the shank member when said second bar is moved rearwardly with respect to said handle member.

4. In a screwdriver, a shank member having a bit portion adapted to engage the kerf of a screw, a sleeve member slidable on said shank member, a pair of opposed screw-head-engaging jaw elements pivotally secured to said sleeve member, inter-engaging cam means on said shank member and jaw elements formed and arranged to contract said jaw elements around the kerf-engaging portion of the shank member responsive to rearward axial movement of said sleeve member with respect to said shank member, a handle member slidable on said sleeve member, a gear rotatively carried by said shank member, a first rack bar fixed to said handle member meshing with said gear, a second opposing rack bar slidably in said handle member also meshing with said gear, said rack bars meshing with the gear at diametrically opposite

points on the gear, said second rack bar normally bearing on said sleeve member to oppose rearward movement thereof with respect to said shank member, a spring bearing between the handle member and sleeve member in opposition to said second rack bar, said spring being formed and arranged with respect to the handle member and sleeve member to move the sleeve member rearwardly with respect to the shank member when said second bar is moved rearwardly with respect to said handle member, and means for at times locking said second bar in rearwardly moved position in said handle member.
